COMBINED DISPLAY AND DISPENSING RACK

Donley C. Brake, 3305 Campus Ave.,
Claremont, Calif. 91711

Filed Mar. 24, 1969, Ser. No. 16,409

Term of patent 14 years

Int. Cl. D6—01

U.S. Cl. D80—9

FIG. 1 is a front perspective view taken from one side of a combined display and dispensing rack showing my new design;

FIG. 2 is an elevational view taken from the side opposite that shown in FIG. 1; and

FIG. 3 is a rear elevational view thereof.

The broken line representation of a cash register in FIG. 1 is for purposes of illustration only, it being understood that the support base has been omitted from FIGS. 2 and 3 for convenience of illustration.

I claim:

The ornamental design for a combined display and dispensing rack, substantially as shown and described.
